OTHER PUBLICATIONS

Office Action dated Jan. 11, 2017 in respect of Design U.S. Appl. No. 29/508,985.

Primary Examiner — Lakiya Rogers*Assistant Examiner* — Harold E Blackwell, II(74) *Attorney, Agent, or Firm* — Bereskin & Parr LLP/S.E.N.C.R.L., s.r.l.(57) **CLAIM**

The ornamental design for a curtain rod finial, as shown and described.

DESCRIPTION

FIG. 1 is a side perspective view of a curtain rod finial; FIG. 2 is a first end view of the curtain rod finial of FIG. 1; FIG. 3 is a side view of the curtain rod finial of FIG. 1; and, FIG. 4 is a second end view of the curtain rod finial of FIG. 1.

The broken lines in the drawings illustrate portions of a curtain rod finial which form no part of the claimed design.
